UNITED STATES PATENT OFFICE.

WILLIAM C. SCHRENKEISEN, OF MOUNT VERNON, NEW YORK, ASSIGNOR TO HILL LAUNDRY EQUIPMENT CO. INC., OF LONG ISLAND CITY, NEW YORK, A CORPORATION OF NEW YORK.

SHOE DRIER.

Application filed October 27, 1927. Serial No. 229,212.

This invention relates to drying apparatus and more particularly to a drying apparatus intended for use in hotels, apartment houses and the like for drying the shoes of the occupants or visitors which have been partially or wholly wet through due to exposure to rain, snow or other moisture. It may also be used wherever it is desired to dry moisture from shoes and similar articles.

10 Among the objects of the invention are to provide a device which will quickly and efficiently dry boots, shoes and similar objects; to provide a device in which shoes may be dried by the application of heat to the interior thereof; to provide a device of this character which is simple, cheap and efficient in operation; and generally to improve the art of evaporating any liquid from the shoes and other like objects either during the process of manufacture or afterward.

Other objects and advantages of the invention will be apparent from a reading of the following specification and subjoined claims when taken in connection with the accompanying drawings, in which:

Figure 1 is an elevation partly in vertical section of my device;

Fig. 2 is a section taken substantially on the line 2—2 in Fig. 1; and

30 Fig. 3 is a fragmentary section similar to Fig. 2 but showing a modified form of the device.

I have found that it is more efficient to dry shoes by forcing the heated air used for drying into the interior of the shoe than by subjecting the shoe to external heat, an air blast or both. This is due, in the event that the moisture has penetrated to the inside of the shoe, to the fact that external heat will not evaporate the water from the inside to any material extent; and in the event that the moisture has only partially penetrated the material of the shoe, to the fact that if the drying is done from the outside, the surface of the leather is dried first forming a relatively hard and substantially water-impermeous skin which prevents the evaporation of water through the outside, the result being that if the shoe is dried out at all, the water must pass completely through the leather and out the inside of the shoe, this action resulting in a complete saturation, for a time at least, of the entire thickness of the leather in the shoe, so that when it is

dried, the shoe is non-pliable and extremely uncomfortable to the wearer until it has been again limbered up. By the use of my method, the heat is applied from the inside which in the case under consideration is dry, so that the water is evaporated through the outside of the shoe, leaving the leather in a substantially pliable condition by the avoidance of the skin effect above referred to.

To accomplish the above described results, I preferably make use of a means, such as a fan blower, for forcing air in the desired direction, an air-heating means and suitable air-conducting means for directing the heated air into the interior of the shoe. In the accompanying drawings I have shown a device embodying my invention for carrying out the drying in a quick, cheap and efficient manner.

Referring to Figs. 1 and 2, I employ a cabinet generally indicated at 1 having suitable doors 2 to give access to the interior thereof and having a partition 3 separating the top chamber or air header 4 from the lower or drying chamber 5. Any desired means such as a centrifugal fan blower 6 may be employed to force air into the chamber 4 preferably through an opening 7 in one end, the blower being driven by any suitable source of power, such as the electric motor 8.

I employ any suitable form of air heating means, such as an electric resistance unit 9, preferably located within the air header 4, but it is to be understood that steam coils, gas or coal burning devices and various other sources of heat may be used if desired.

For the purpose of conducting the heated air from the header 4 into the shoe drying compartment 5, I employ a plurality of tubes or ducts 10 suitably secured in the wall 3 preferably cut off obliquely at their upper ends as shown at 11 and having the high parts 12 of the oblique walls turned in the direction of the opening 7. This has the effect of making turbulent the flow of the air within the header 4, thus retarding it to some extent and permitting it to be heated to the desired temperature by the heater 9.

The ducts 10 are extended downwardly and are open at the lower end to direct the heated air out at that point. The shoes, shown at 13 and 14 are supported in the desired position to receive the air inside. I support them in that position by providing

hooks 16 directly on the ducts 10 which engage with loops or other supporting means on the shoes.

Referring to Fig. 3 in which certain parts 5 are similar to the corresponding parts in the form shown in Figs. 1 and 2 and are correspondingly numbered, I have shown a shelf 17 upon which the shoes, one of which is shown at 18, may be supported in alignment 10 with the jets of air coming through the ducts 10. In this form, however, the shoe is completely below the end of the duct, which, however, is directed toward the opening 15 therein, so that drying takes place from both the inside and the outside.

As it is obvious that many modifications and changes might be made in my device without the exercise of invention, I do not wish to be limited except by the scope of 20 the appended claims.

I claim:

1. A shoe drier comprising a cabinet, a compartment at one side thereof constituting an air header, means for blowing air into 25 said header from one end, an air heater in said header, a plurality of ducts extending through the wall separating the header compartment from the interior of the cabinet, said ducts having their ends within the 30 header cut off obliquely and their high sides toward the air inlet end of the header, whereby to cause a turbulent flow of the air and permit it to be thoroughly heated, and supporting means for the shoes to be dried 35 so arranged that one of said ducts may be extended into the interior of each shoe.
2. A shoe drier comprising a cabinet, a wall adjacent to the top thereof dividing the interior of the cabinet into an upper air 40 header and a drying compartment therebeneath, an air blower communicating with one end of said header, an air heater in said

header, a plurality of ducts extending through said wall, said ducts having their ends within the header cut off obliquely and 45 the high sides toward the air inlet end of the header, whereby to cause a turbulent flow of the air and permit it to be thoroughly heated, and supporting means for the shoes to be dried so arranged that one 50 of said ducts may be extended into the interior of each shoe.

3. A drier comprising a cabinet, a compartment therein constituting an air header, means for blowing air into said header from 55 one end, an air heater, a plurality of ducts extending through the wall of the header compartment, said ducts having their ends within the header cut off obliquely and their high sides toward the air inlet end of the 60 header, to cause a turbulent flow of the air and permit it to be thoroughly heated, and supporting means for the hollow article to be dried so arranged that one of said ducts may be extended into the interior of each 65 article.

4. A shoe drier comprising a cabinet having walls enclosing it on all sides, a wall adjacent to the top thereof dividing the interior of the cabinet formed by said walls 70 into an upper air header and an enclosed drying compartment therebeneath, an air blower communicating with one end of said header, an air heater in said header, a duct passing through said wall into the drying 75 compartment, and means on said duct for suspending in said enclosed drying compartment a shoe to be dried, whereby the duct is adapted to direct heated air into the interior of the shoe from which it escapes into 80 the compartment.

In testimony whereof I have hereunto affixed my signature.

WILLIAM C. SCHRENKEISEN.
